UNITED STATES PATENT OFFICE.

ARTHUR J. VANCE, OF PAINESVILLE, OHIO, ASSIGNOR TO THE COE MANUFACTURING COMPANY, OF PAINESVILLE, OHIO, A CORPORATION OF OHIO.

DRIER FOR SHEET MATERIAL.

Application filed August 1, 1924. Serial No. 729,617.

This invention relates to driers of veneers and the like wherein the material under treatment is conveyed through the drier by means of a series of pairs of rollers.

5 More especially the invention relates to roll supported mechanism and conveyor rolls for such driers.

In driers of this kind it has been common to support the conveying rolls in even- 10 ly spaced pairs, the upper rolls being free to rise and fall to accommodate the different thickness of material being treated. Furthermore, such driers are usually provided with an inner roll supporting frame having 15 spaced vertical side members which carry oppositely disposed connecting bars wherein are formed bearings for the roll journals. Heretofore these bars have been commonly of channel cross section having U-shaped 20 slots extending downwardly from the upper part and surrounded by suitable flanges, the bar also having journal openings in the lower part surrounded by annular flanges. Since the distance between the 25 centers of the conveyor rolls of each pair is controlled, at its minimum, by the roll diameters and the bottom flange of the channels is usually level with the bottom of the lower bearing flanges, these supporting bars 30 have considerably more material than is necessary for the purpose and consequently are excessive in weight.

Moreover, it is possible, by careless feeding of the veneer, to lap the edge of one 35 sheet over the edge of another sheet. Should this lap occur near the middle of the length of the rolls, the unusual thickness between the rolls at this point may cause the lighter end of the top roll to rise sufficiently for its 40 journal to get out of the U-shaped slot. In addition to this the even spacing of the pairs of rolls tends to cause corrugations in some of the materials passed between them, especially when the material is of a composition 45 such as is used in the manufacture of fiber board.

The important objects of the present invention are to avoid the difficulties of such arrangements and to improve the construction 50 of such conveyors by providing a form of roll supporting bar wherein the material

will be reduced to a practical minimum in weight while retaining all necessary strength, the rolls will be so spaced as to prevent corrugation, and means will be provided for eliminating the jumping or lifting of the upper rolls out of their bearings. 55

With these and other objects in view one embodiment of the invention will now be described in detail and then specifically 60 pointed out in the claims, reference being had to the accompanying drawings, wherein:

Figure 1 is a partial side elevation showing a portion of a roll supported frame 65 constructed in accordance with this invention.

Figure 2 is a transverse section therethrough.

Figure 3 is a plan view on an enlarged 70 scale of one of the roll bearing bars.

Figure 4 is a side elevation of such a bar.

Figure 5 is a side elevation of a modified 75 form of bar, arranged for preventing corrugation.

Figure 6 is an end view thereof.

Figure 7 is a section on the line 7—7 of Figure 4.

Figure 8 is a detail showing a pair of 80 improved rolls for use herewith.

Figure 9 is an enlarged detail showing the top roll retaining bar.

Figure 10 is a transverse section through a pair of felt covered rolls.

Any suitable form of construction may be 85 used to support the roll bearing bars, the improvement in the construction of which is one of the essential features in this invention. For instance, a conveyor frame may be constructed having vertical members 10 disposed opposite each other and connected by longitudinal members 11 supporting the heater coils 12. The rolls are shown as arranged in pairs, the lower roll of each pair being indicated at 13 and the upper at 14. 90 These rolls are provided with journal ends 15 and 16 respectively. Each of the roll bearing bars is preferably formed as a single unit of cast or pressed metal and is provided with a web 17 and a bottom flange 18, the bottom flange inclining upwardly from the center toward both ends so that the web de- 95 100

creases in height from the center toward said ends. This construction distributes the weight of the material more advantageously, the web being progressively deeper from the 5 ends to the center where greater rigidity and strength is required. At intervals along the top portion of the web there are provided U-shaped journal receiving slots 19 surrounded by reinforcing flanges 20 and the 10 depth of these slots is considerably greater than the width so that the upper journals 16 held therein may slide vertically thus enabling the rolls of each pair to vary in distances between centers and accommodate 15 different thicknesses of the material being treated. As previously mentioned this material may be carelessly fed at times so that the material overlaps near the middle and causes the upper journals 16, if not prevented, to lift entirely out of the slots 19. To avoid this certain of the flanges 20, preferably the end flanges, are laterally extended as at 21 and provided with threaded openings 22 to receive the bolts 23 which secure 25 a hold down or cover plate 24 to the top of the roll bearing bar thus covering in all of the upper bearing slots. Below each of the upper bearing slots the bar carries a tubular flange 25 and the center flange is so positioned that the flange 18 merges into its bottom portion. These flanges 25 have their centers in horizontal alinement and by this means the portions of the flange 18, between the bearing flanges 25, intersect these 30 flanges at points which gradually become higher as the ends of the bar are approached. The upper and lower flanges are preferably connected by short ribs 26. At each end the bar is provided with bosses 27 having openings 28 for the reception of bolts 29 by which the bearing bar is secured to the uprights 10.

In the form of the device as shown in Figure 4 it will be seen that the spacing of 45 the pairs of rolls is uniform, that is to say the distances longitudinally of the bar between the adjacent bearing centers are uniform. In treating certain material such uniform spacing tends to produce corrugation and it is found that by having a set, or sets, of roll bearing bars located at a 50 place in the length of the drier when the material to be dried is in a condition to be set, or take permanent shape, and having spacing of the rolls in said bearing bars irregular and unequal in distance from center to center as shown in Fig. 5, such corrugating is prevented. It will be obvious, of course, that whatever spaces are adopted the 55 bearings on one side of the conveyor will be spaced in conformity with the bearings on the other side. It will be noted that the lower bearing openings are larger than the upper, this being for the purpose of permitting roller bearings 30 to be used.

While the rolls shown in Figure 1 are uniform throughout the length certain cases arise where it is advisable to use an upper roll such as is shown in Figure 8 wherein it will be seen that the center portion of the 70 upper roll is reduced as at 31 to provide end flanges 32 which rest on the lower roll 13, the engagement being at the ends of the body of the lower roll. Preferably these flanges 32 are of the same diameter as the 75 body of the roll 13. The effect will be the same by having the body of the upper roll 31 of the same diameter as the lower roll 13 and having the flanges 32 of greater diameter than either roll and dispense with 80 the gears, or star wheels, on these two rolls, driving the top roll by friction through the flange. When this type of roll is used the material passing through does not lift the 85 upper roll, the function of the latter then being a guide to the material to be dried and to prevent the air currents from lifting the material off the lower rolls.

With the arrangement here shown and 90 described material used in the roll supporting bar is so distributed that the necessary strength is obtained without undue weight, the corrugating of the material being treated is eliminated, and the upper rolls are prevented from jumping out of their bearings. 95

Another special type of roll is shown in Figure 10, where 13 is a metal lower roll, of any pair, covered with felt 33, and 14 is its corresponding top roll, covered with 100 felt 34. Some materials which would be damaged by actual contact with the metal surface of the rolls can be passed between felt covered rolls without injury. Furthermore, the felt having a great capacity for absorbing moisture, rapidly extracts the 105 moisture from the material at the point of contact, and as the rolls revolve, the felt gives up its moisture to the currents of warm air. This action will insure more rapid 110 drying of materials that must be dried in comparatively low temperatures.

Changes in this specific form will be obvious to engineers, such changes being entirely within the scope of the present invention so it is not desired to limit the invention 115 to this precise form but rather it is desired to include all such as properly come within the scope claimed.

Having thus described the invention, what 120 is claimed as new, is:

1. A conveyor roll bearing bar having a web provided with horizontal upper edge portions interrupted at intervals by U-shaped journal receiving slots each having a reinforcing flange therearound, tubular bearing flanges carried by the lower portion of said web, said web being deepest at its central portion and gradually lessening in depth toward the ends, said tubular bearing flanges at the center of the bar having their 125 130

lower parts flush with the bottom of the journal receiving openings spaced longitudinally of the bar, each center to center distance between adjacent openings being different from the remaining center to center distances. ¹⁰

2. A roll bearing bar having transverse journal receiving openings spaced longitudinally of the bar, the distances between centers of adjacent openings being unequal. In testimony whereof I affix my signature.

3. A roll bearing bar having transverse
